UNITED STATES PATENT OFFICE.

JAMES TIMMS, OF MALTA, ASSIGNOR TO HIMSELF, HUGH M. COCHRAN,
AND JOSEPH F. SONNASTINE, OF McCONNELLSVILLE, OHIO.

IMPROVEMENT IN PITMAN-CONNECTIONS.

Specification forming part of Letters Patent No. **150,803**, dated May 12, 1874; application filed
April 18, 1874.

To all whom it may concern:

Be it known that I, JAMES TIMMS, of Malta, Morgan county, Ohio, have invented a new and useful Improvement in Pitman-Connections, of which the following is a specification:

Figure 1 is a top view of my improved pitman-connection, and Fig. 2 is a side view of the same.

Similar letters of reference indicate corresponding parts.

My invention has for its object to furnish an improved device for taking up the wear and the consequent lost motion, and which shall be simple in construction, convenient in use, and effective in operation. The invention consists in the combination of the sleeve or bearing and the lock-nuts with the head or lug of the sickle-bar, and the pitman having a screw-thread cut upon it, as hereinafter fully described.

A represents the sickle-bar, which is provided with a lug or head, a' , to receive the hook b^1 formed upon the end of the pitman B.

Upon the lower part of the pitman B is placed a sleeve, C, upon one side of the lower end of which is formed a toe or head, c' , which is recessed to fit upon the sickle-bar head a' . The sleeve C is held down by lock-nuts D, placed upon a screw-thread cut upon the pitman B. By this construction, by turning down the nuts D the wear will be taken up to prevent lost motion caused by the wear, so that the hook can be used until worn out.

Having thus described my invention, I claim as new and desire to secure by Letters Patent—

The combination of the sleeve or bearing-head C c' and lock-nuts D with the head a' of the sickle-bar A, and the pitman B b^1 , having a screw-thread, b^2 , cut upon it, substantially as herein shown and described.

JAMES TIMMS.
